CLAIM

The ornamental design for a brushguard, as shown and described.

DESCRIPTION

FIG. 1 is a front perspective view of a brushguard showing our new design;

FIG. 2 is a back perspective view thereof;

FIG. 3 is a front view thereof;

FIG. 4 is a back view thereof;

FIG. 5 is a top view thereof;

FIG. 6 is a bottom view thereof;

FIG. 7 is first side view thereof; and,

FIG. 8 is a second side view thereof.

The broken lines are for the purpose of illustrating portions of the brushguard and form no part of the claimed design.

1 Claim, 6 Drawing Sheets
